[57] CLAIM

The ornamental design for a radiator grill of a motor vehicle, as shown and described.

DESCRIPTION

FIG. 1 is a perspective view of a radiator grill of a motor vehicle showing a first embodiment of our new design;

FIG. 2 is a front view thereof;

FIG. 3 is a rear view of thereof;

FIG. 4 is a top view thereof;

FIG. 5 is a bottom view thereof;

FIG. 6 is a left side view thereof;

FIG. 7 is a right side view thereof;

FIG. 8 is an enlarged sectional view taken along the line 8—8 in FIG. 2;

FIG. 9 is an enlarged sectional end view taken along the line 9—9 in FIG. 2;

FIG. 10 is an enlarged sectional end view taken along the line 10—10 in FIG. 2;

FIG. 11 is a perspective view of a radiator grill of a motor vehicle showing a second embodiment of our new design;

FIG. 12 is a front view of FIG. 12;

FIG. 13 is a rear view of FIG. 12;

FIG. 14 is a top view of FIG. 12;

FIG. 15 is a bottom view of FIG. 12;

FIG. 16 is a left side view of FIG. 12;

FIG. 17 is a right side view of FIG. 12;

FIG. 18 is an enlarged sectional view taken along the line 18—18 in FIG. 12;

FIG. 19 is an enlarged sectional end view taken along the line 19—19 in FIG. 12; and,

FIG. 20 is an enlarged sectional end view taken along the line 20—20 in FIG. 12.

The portion of the radiator grill shown in broken lines is for illustrative purpose only and forms no part of the claimed design.
